UNITED STATES PATENT OFFICE

2,402,246

MANHOLE COVER LOCKING MECHANISM

Arthur J. Gillette, Chicago, Ill.

Application March 6, 1944, Serial No. 525,148

1 Claim. (Cl. 70—168)

1

My invention belongs to that general class of devices known as manhole covers, and more particularly to mechanism for removably locking the cover at the open end of the manhole.

The invention has among its objects the production of a device of the kind described which is simple, inexpensive, convenient, efficient and satisfactory. It has particularly as an object the production of a manhole cover and locking means therefor whereby the manhole cover cannot be readily removed by unauthorized persons.

The invention has as a further object the production of a locking mechanism of the kind described which cannot be manipulated or operated except by the use of a key of simple construction in the possession of one authorized to remove or replace the cover. A further object is the production of an auxiliary closure arranged to cover a keyhole through the manhole cover and which may be moved out of the way when it is desired to operate the locking mechanism at the under side of the manhole cover.

Many other objects and advantages of the construction herein shown and described will be obvious to those skilled in the art from the disclosure herein given.

To this end my invention consists in the novel construction, arrangement and combination of parts herein shown and described, and more particularly pointed out in the claim.

In the drawing, wherein like reference characters indicate like or corresponding parts:

Fig. 1 is a plan view of my improved manhole cover in position at the mouth of a manhole;

Fig. 2 is a sectional view of the same taken substantially on line 2—2 of Fig. 1;

Fig. 3 is a sectional view taken substantially on the line 3—3 of Fig. 2;

Fig. 4 is a sectional view taken substantially on line 4—4 of Fig. 2;

Fig. 5 is a plan view of an auxiliary closure arranged at the under side of the manhole cover;

Fig. 6 is a similar view of a modified construction; and

Fig. 7 is a view in elevation of a key suitable for unlocking the cover as well as to move the auxiliary closure.

Referring to the drawing, 1 represents a manhole cover, generally of cast iron or other suitable material of the desired size and shape arranged to cover the mouth of a manhole 3 formed by the manhole structure 2. Ordinarily, a top annular member 4 of concrete or other suitable material is arranged at the mouth of the manhole, the same being provided with a ledge 5

upon which the cover rests when in closed position.

Carried by the manhole cover at the underside is a locking bar 6 of a length to engage with the manhole structure, as shown, with the under face 7 of the top member 4. Carried at the under side of the cover 1 is a threaded rod or bolt 8 provided with a head 9, the bolt threadedly engaging at 10 with the bar 6, the lower end of the bolt being preferably headed or enlarged as indicated at 11. As shown, the head 9 of the bolt is carried from a supporting member 12, 13 being a spacer arranged between the member 12 and the cover, it being understood, however, that any equivalent for the member 12 and spacer 13 may be employed for the purpose. The member 12 also carries guides 14 which are arranged to guide the bar 6 when the bolt 8 is rotated and prevent rotation of the bar 6 relative the cover when the bolt is turned to lock or unlock the cover.

Provided in the cover is an opening or keyhole 16 which is in registry with the bolt head 9. The bolt as shown is provided with a recess 17 for receiving the end 19 of a key 18, the end 19 being insertable through the opening 16 so that the bolt may be engaged and turned from the exterior of the cover to raise or lower the bar 6. To prevent the admission of dirt into the recess 17 through the opening 16 in the cover I provide a closure or auxiliary cover 20 arranged at the under side of the cover 1 which may be secured in place by a member 21 rigidly secured to closure 20 and extending through the cover 1, the same being provided with a recess 23 in which the end 24 of the key 18 may be inserted. The closure 20 is provided with an opening 22 which may be brought into registry with the opening 16 through the cover 1 so that the end 19 of the tool or key may be inserted through the opening 16 and engage the bolt 8 to turn it.

In the modified closure shown in Fig. 6, 25 represents the closure which may be secured in place on the cover by a small bolt or screw 26 having a recess 27 corresponding with the recess 23 in the bolt 21. In this case the opening 28 in the closure and the bolt 26 are shown arranged off-center.

In applying the manhole cover to the manhole, the bolt 8 is turned so that the locking bar 6 is spaced from the member 12 as shown in the dotted lines in Fig. 2. The cover 1 may then be tilted to permit one end of bar 6 to be seated and underlie the under face 7 of the ring 4 and then the opposite end of the bar 6 is seated below the ring 4, after which the cover 1 may be seated

on the face 5. Assuming the closure member 20 is as shown in Fig. 2 in the dotted position, the end 19 or key of the wrench 18 may be inserted through the opening 16 to engage the bolt head in the recess 17. As the bolt 8 is turned by means of the key or wrench, the bar 6 is moved up into engagement with the face 7, as shown in Fig. 2. The wrench 18 may then be removed and the end 24 inserted in the recess 23 of the bolt 21 and the bolt 21 turned, thereby turning closure 20, to which the bolt 21 is rigidly secured, and rotating the same sufficiently to close the keyhole or opening 16 at the under side of the closure. It will thus be obvious that the manhole cover 1 is securely locked in place and the admission of dust, dirt, water, etc. through the opening 16 to the under side of the cover is prevented. To remove the cover 1 the operations are reversed.

The device not only securely locks the manhole cover in place, but prevents its unauthorized removal, thereby preventing the same from being stolen or being removed by children curious to see what the manhole is like. Where the same is in the street, the manhole cannot easily be displaced by vehicles passing over the same.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

A locking mechanism for manhole covers and the like of the kind described for use on a man-hole structure having an annular internal flange at its upper end, and in combination, a circular cover, a supporting member, separate spacers located between the cover and supporting member and secured to the cover and supporting member, one at each side of the center of the cover to leave a free space between said spacers, a locking bar of greater length than the internal diameter of said flange adapted to be engaged with the underside of the flange and at any place thereon, a bolt having a socketed head disposed in the space between said spacers and carried by said supporting member at the underside of the cover and threadedly engaging said locking bar, said cover being provided with a key hole, opening through the same in registry with the bolt, and upright guide means carried by the supporting member for guiding the locking bar and preventing relative rotation between the cover and locking bar, said bolt being of a length to space the locking bar away from the cover sufficiently for one end of the bar, when the cover is tilted, to be inserted under the flange and the other end of the bar then passed through the opening, and the ends of the bar being drawn up against the flange by the bolt.

ARTHUR J. GILLETTE.
